STYLE AND TITLE OF HENRY TAUBEL & SON.

YARN-FEEDING DEVICE FOR KNITTING-MACHINES.

1,187,527.

Specification of Letters Patent. Patented Apr. 27, 1915.

Application filed November 8, 1912. Serial No. 729,462.

To all whom it may concern:

Be it known that we, ROBERT S. PHILLIPS and BENJAMIN H. PHILLIPS, both citizens of the United States, residing in Riverside, 5 Burlington county, New Jersey, have invented certain Improvements in Yarn-Feeding Devices for Knitting-Machines, of which the following is a specification.

Our invention relates to that class of yarn feeding devices for knitting machines which are intended to feed either a single or a double yarn to the needles, the object of our invention being to so construct such a yarn feeding device that, when the double yarn 15 is being fed, the yarps will be so disposed as to insure the presentation of a selected one of the same on the surface of the knitted web which is being produced. This object we attain in the manner hereinafter set forth, reference being had to the accompanying drawing, in which—

Figure 1 is a side elevation of a yarn feeding device constructed in accordance with our invention; Fig. 2 is a top or plan view 25 of the same; Fig. 3 is a view, partly in side elevation and partly in transverse section, on the line *a—a*, Fig. 2; Fig. 4 is a side elevation showing the parts in a different relation to each other from that represented in Fig. 1, and Fig. 5 is a side elevation of 30 one of the members of the mechanism detached from the others.

In knitting hosiery it is a common practice to employ, in knitting certain parts of the web, a single yarn, as for instance one of cotton, and, in knitting other parts of the web, to combine with said cotton yarn a 35 yarn of different material, such as silk, or artificial silk. In these portions of the web 40 in which the double yarn is employed it is desirable to present the second or supplementary yarn on the surface of the web, and the object of our invention is to so construct the yarn feeding device as to insure this result.

In the drawing, 1 represents a standard fixedly mounted upon the cam cylinder of the machine and having pivotally mounted upon it, at 2, a lever 3, which carries the 45 main yarn feed, the latter in the present instance comprising a tubular guide 4 and a guide 5 serving as a continuation of the

same, said guide 5 being formed in the usual latch guard 6 of the machine. This particular construction of main yarn feed is 55 not essential, however, so long as said feed is mounted upon the lever 3. The normal position of the lever 3, that is to say, the position assumed by it when the single yarn is being fed to the needles, is that shown in 60 Figs. 1 and 3, this position being determined by contact of the rearwardly extending arm of the lever 3 with a set screw 7 carried by a projecting member of the standard 1, as shown in said Fig. 3. 65

Mounted upon the standard 1 by means of a pivot pin 8 is an arm 9, whose upper end bears upon the rearwardly extending arm of a supplementary yarn feeding lever 10 whose forward or feeding arm plays in a recessed 70 portion of the latch guard 6, the contact surface of the rear arm of said lever 10 and the arm 9 being so formed that, as said arm 9 is pushed forwardly in the direction of the arrow *a* Fig. 1, it will raise the rear arm 75 of the lever 10 and depress the forward arm of the same so as to bring the yarn fed thereby into position to be fed to the needles of the machine, as shown in Fig. 4, movement of the arm 9 in a direction the reverse 80 of that indicated by the arrow *a* permitting the rear arm of the lever 10 to drop and its forward arm to rise so as to carry the yarn fed thereby out of feeding position in respect to the needles, as shown in Fig. 1. 85 A coiled spring 11 connects a pin 12 on the lever 10 and a pin 13 which projects from the standard 1 through a segmental slot 14 in the arm 9, so that it does not interfere with the free swinging movement of the latter, 90 the tendency of the spring 11 being to impart downward movement to the rear arm of the lever 10 and rearward movement to the arm 9 owing to the cam-like action of the contact surfaces of said lever and arm. 95

Suitably mounted on the standard 1 is a horizontal lever 15 carrying at each end an anti-friction roller 16 these rollers being located in different horizontal planes because of the bending downward of one end of the 10 lever 15, as shown in Fig. 5, and said lever 15 can be vibrated by contact of one or other of the rollers 16 with a plate which is mounted so as to be vertically adjustable into the

plane of either of the rollers 16, the plate having rotary movement past the lever or the lever having rotary movement past the plate as is common in machines of this type, 5 and the rollers 16 being set in different circumferential as well as different horizontal planes so that when the plate contacts with one roller, say the higher one, it will move the lever 15 in the direction of the arrow *y* 10 Fig. 2 and when it contacts with the other or lower roller it will move said lever in a direction opposite to that indicated by the arrow *y*.

When the lever 15 is moved in the direction of the arrow it will contact with the back of the arm 9 and will move the same from the position shown in Fig. 1 to that shown in Fig. 4, thereby shifting the supplementary yarn feeding lever 10 from the inoperative position shown in Fig. 1 to the operative position shown in Fig. 4. In order, however, to insure the application of the supplementary yarn to the needles so that it will lie upon the face of the fabric, 25 we find that when the supplementary yarn feed is moved to feeding position the main yarn feed should be moved away from the normal position occupied by it when the main yarn alone is being fed to the needles, 30 and we therefore provide for lifting said main yarn feed slightly when the supplementary yarn feed is lowered into operative relation to the needles, said lift being effected by means of a cam 17 (Fig. 3) on the lever 15, which cam, as said lever 15 is moved in the direction of the arrow *y*, acts upon the rear arm of the lever 3 to depress the same and thereby to lift the outer arm of said lever carrying the main yarn feed, as 35 shown in Fig. 4, the lever 3 resuming its normal position when the supplementary yarn feed lever 10 is raised to inoperative position, as shown in Fig. 1, when the lever 15 is swung in a direction opposite that indicated by the arrow in Fig. 2. By this 40 means the application of the supplementary yarn to the needles is at a point so much below that of the main yarn as to insure the

presence of the supplementary yarn on the face of the knitted web.

50

We claim:

1. The combination in a plating device for knitting machines of the main and supplementary yarn feeds, with means for moving the supplementary yarn feed into and out of operative relation to the needles, means for retaining the main yarn feed always in feeding position in respect to the needles, and means for shifting the position of the main yarn feed when the supplementary feed is moved into feeding position. 60

2. The combination in a plating device for knitting machines of the main yarn feeding lever and supplementary yarn feeding lever, means for retaining the main yarn feed always in feeding position in respect to the needles, an actuating lever, and means whereby said actuating lever is caused to move the supplementary yarn feeding lever 70 from inoperative to operative position and at the same time to shift the main yarn feeding lever from its normal feeding position to an abnormal feeding position.

3. The combination in a plating device for 75 knitting machines of the main yarn feeding lever and the supplementary yarn feeding lever, means for retaining the main yarn feed always in feeding position in respect to the needles, an actuating lever having a cam 80 for acting upon the main yarn feeding lever to move it from normal to abnormal feeding position, and means whereby the movement of the actuating lever is transmitted to the supplementary yarn feeding lever to move 85 the same from inoperative to operative position.

In testimony whereof, we have signed our names to this specification, in the presence of two subscribing witnesses.

ROBERT PHILLIPS.
